UNITED STATES PATENT OFFICE.

GEORGE H. MARCOPoulos, OF CLEVELAND, OHIO.

VENDING-MACHINE.

1,228,799.

Specification of Letters Patent.

Patented June 5, 1917.

Application filed February 1, 1915. Serial No. 5,352.

To all whom it may concern:

Be it known that I, GEORGE H. MARCOPoulos, a citizen of the United States, residing at Cleveland, in the county of Cuyahoga and State of Ohio, have invented a certain new and useful Improvement in Vending-Machines, of which the following is a full, clear, and exact description, reference being had to the accompanying drawings.

10 This invention relates to vending machines that are of a size and style especially suitable for use on railway cars, and other public conveyances, or in theaters, music halls and like places of entertainment, and that 15 are adapted for attachment to the backs of seats or to the walls of cars, in the usually narrow spaces between the windows.

The object of the invention is to provide 20 a vending machine of the above nature that is extremely simple of construction and correspondingly cheap of production; that may be very conveniently operated; that may be opened, by an authorized person, to allow him to gain access to the goods container or 25 magazine, and to the coin receiving compartment; that is provided with a removable goods container whereby an empty container may be removed and a full one substituted therefor in a very brief interval of time; 30 wherein the ejecting mechanism is practically indestructible from any reasonable amount of usage; and wherein a coin constitutes a part of the ejecting mechanism, the same being moved into contact with the 35 article to be ejected, and acting to shove the same from the machine.

The above objects are attained in a machine constructed in accordance with the accompanying drawing, wherein Figure 1 is 40 a perspective of the vending machine of my invention; Fig. 2 is a central vertical section through the machine; while Figs. 3 and 4 are horizontal sections on the correspondingly numbered section lines of Fig. 2.

45 The casing of the machine, which comprises a bottom wall 1, side walls 2 rear wall 3, and top wall 4, is open at the front from top to bottom, and the open side of the casing is adapted to be closed by a door 5, that 50 is provided with a peripheral flange 6 which overlies the front edges of the side, top, and bottom walls; and the left hand side of the

door is hinged to the corresponding side wall of the casing, as shown at 7. A suitable lock (not shown) is used for retaining 55 the door closed, and the same may be located within the casing to coöperate with the right hand edge of the door. It will be noted that the lower portion of the casing is somewhat wider from front to rear than the upper portion thereof, and that the door 5 is shaped 60 to correspond thereto. The portion of the door that covers the goods container or magazine is provided with an observation slot 8, that may be closed by a pane of glass 9, and 65 below this slot there is a transverse opening 10 through which the goods may be ejected. A coin slot 12 is located adjacent the right hand edge of the door, and the lower, offset portion of the door is provided with an 70 opening 13 through which the operating handle of the ejecting mechanism extends. The horizontal ledge 14 that is formed between the upper and lower portions of the door, provides a shelf onto which the goods 75 are delivered by the ejecting mechanism.

Extending inward from the side walls, and from the front of the casing and between the narrower and wider portions of the casing, is a ledge 15, and spaced below 80 said ledge is a horizontal partition 16, that has an opening 17. The forward edges of the ledge 15 and the partition 16 are connected by a plate 18. Supported by and between the rear wall 3 and the plate 18, parallel to and adjacent each of the side walls 2, is a rod 19. A coin mover 20, having a coin receiving slot 21, has each of its ends guided upon one of the aforesaid rods, and a spring 22, supported upon each of the rods 19, and 85 confined between the plate 18 and the front surface of the coin mover 20, acts to normally retain the mover in the rear of the casing, and in a position to receive a coin from a chute 23, that is located in the right hand side of the casing and the forward end of which registers with the coin receiving opening 12 of the door. A stem 24 that is 90 attached to the coin mover, projects forwardly therefrom and through a guiding aperture in the plate 18, that registers with the opening 13 in the door. Where the forward end of the stem 24 projects beyond 95 the door, it is provided with a ring 25 that

may be grasped by the operator when he wishes to actuate the ejecting mechanism.

The goods container or magazine consists of a holder comprising a rear wall 26 and 5 side walls 27, the forward edges of the latter being turned inward to form flanges 28. The aforesaid walls and the flanges 28 combine to form a guide for the rectangular packages 29 within which the goods are 10 contained. A drop or shield 30 is hinged to the door in a position to hang across the opening 10, to protect the packages 29. A flange 31 extends along each side and across the front of the bottom of the goods container and forms a support for the lowest package; and the goods container is supported, in turn, upon the flange 15. Ribs 32 are carried by the rear wall 3 of the casing to form stops for the goods carrier to 15 properly locate it within the casing, and the bottom of the rear wall 26 of the goods carrier is notched at 33 for a purpose which will be explained during the following description of the operation of the machine.

20 When it is desired to operate the machine, a coin is inserted through the opening 12 and is guided, by the chute 23, to the slot 21 of the coin mover. The lower edge of the coin rests upon the partition 16, while the 25 upper edge reposes within the plane of the lowest package 29. The operator then pulls forward on the ring 25, and through the intervention of the stem 24, draws the coin mover forward against the tension of the 30 springs 22. The upper portion of the coin will engage the rear side of the lowest package and push the same outward through the opening 10, onto the ledge 14, the drop 30 swinging upward to permit of such operation. When the package has been ejected 35 sufficiently to be grasped by the operator, the lower edge of the coin has come into register with the opening 17 in the partition 16, and drops therethrough onto the bottom 40 1 of the casing. Thereafter, the coin mover 45 may be allowed to return to normal position under the influence of a spring 22.

When it is desired to remove the money from the machine, and to replenish the machine with goods, the door may be unlocked and swung open, and the money removed, and a fresh supply of goods either placed into the present goods container, or the empty goods container may be removed, and 50 a full one substituted therefor. The fact that access to both the goods and money compartments is gained through the one door, provides a very quick and convenient method of emptying the machine of money and filling it with a fresh supply of goods.

60 The rear wall 3 is perforated at 34, near its top and bottom, to accommodate means whereby the machine may be secured to a supporting structure; and in the case of such

means as screws being employed for this 65 purpose, the heads may repose within the casing where they cannot be tampered with when the door is closed.

Having thus described my invention what I claim is:—

1. A vending machine comprising a vertically disposed open front casing, a horizontal ledge extending along each side and across the front of the casing near the bottom thereof, a coin mover reciprocable beneath the ledge and having a through slot for the reception of a coin, a shelf extending from the back of the casing forward less than the depth of the casing beneath the coin mover and in a position to support a coin in 80 the slot of the coin mover with the upper edge of the coin above the aforesaid ledge, guides for the coin mover extending from front to back of the casing, springs supported by the guides and interposed between 85 the coin mover and a portion of the casing, an operating member extending forwardly from and connected to the coin mover, there being a coin receiving space provided between the bottom of the casing and the 90 aforesaid shelf, a coin chute extending downward and to the rear along the inside of one side wall of the casing the same being turned at its rear end to deliver a coin, transversely disposed, to the coin mover when 95 the latter is in normal position, the chute being only slightly wider than the thickness of the coin, a goods container supported by the aforesaid ledge and extending upward therefrom to the top of the casing and laterally from the aforesaid coin chute entirely to the opposite side of the casing, and a door for closing the entire front side of the casing, said door having a coin receiving slot 100 that registers with the coin chute, an opening through which the goods may be ejected, and an opening through which the operating member of the coin mover projects.

2. A vending machine comprising a vertically disposed open front casing, a horizontal ledge near the bottom thereof, a coin mover reciprocable beneath the ledge and having a through slot for the reception of a coin, a shelf beneath the coin mover and in a position to support a coin in the slot of the coin mover with the upper edge of the coin above the aforesaid ledge, an operating member extending forwardly from and connected to the coin mover, there being a coin receiving space provided between the bottom 110 of the casing and the aforesaid shelf, a coin chute extending downward and to the rear along the inside of one side wall of the casing and being turned at its rear end to deliver a coin, transversely disposed, to the 115 coin mover when the latter is in normal position, the chute being only slightly wider than the thickness of the coin, a goods container supported by the aforesaid ledge and extending upward therefrom to the top of the casing and laterally from the aforesaid coin chute entirely to the opposite side of the casing, and a door for closing the entire front side of the casing, said door having a coin receiving slot 120 that registers with the coin chute, an opening through which the goods may be ejected, and an opening through which the operating member of the coin mover projects.

tainer supported by the aforesaid ledge and extending upward therefrom to the top of the casing and laterally from the aforesaid coin chute entirely to the opposite side of 5 the casing, and a door for closing the entire front side of the casing, said door having a coin receiving slot that registers with the coin chute, an opening through which the goods may be ejected, and an opening

through which the operating member of the 10 coin mover projects.

In testimony whereof, I hereunto affix my signature in the presence of two witnesses.

GEORGE H. MARCOPOULOS.
